Patented Sept. 7, 1920.

FIG.1.

FIG.2.

Inventor
GLENN H. CURTISS.

By his Attorney *John P. Farley*

UNITED STATES PATENT OFFICE.

GLENN H. CURTISS, OF GARDEN CITY, NEW YORK, ASSIGNOR TO CURTISS AEROPLANE
AND MOTOR CORPORATION, A CORPORATION OF NEW YORK.

AIRPLANE-WING-STRUCTURE TRUSS.

1,351,743.

Specification of Letters Patent. Patented Sept. 7, 1920.

Application filed May 4, 1918. Serial No. 232,486.

To all whom it may concern:

Be it known that I, GLENN H. CURTISS, a citizen of the United States, residing at Garden City, in the county of Nassau and 5 State of New York, have invented certain new and useful Improvements in Airplane-Wing-Structure Trusses, of which the following is a specification.

My invention relates to airplane wing 10 structure trussing systems and is characterized by an arrangement of wiring utilizing a minimum number of wires with resulting maximum proportionate strength. Instead of providing separate lift and drift wires at 15 opposite sides of the fuselage a single wire in each instance is used. These wires extend angularly upwardly and rearwardly from the inner ends of the forward wing beams of the lower wings to the outer ends of the 20 rear wing beams of the upper wings. They take not only a considerable portion of the lift load while in flight but a correspondingly large portion of the drift load as well. Especially is the above arrangement adapt- 25 able to the smaller or speed scout types of airplanes having a shallow chord and more or less limited wing spread. When used in connection with K or similar struts (which prevent deflection of the wings due to twisting strains) trussing of the above character 30 is adequate.

In the drawings, wherein like characters of reference designate like or corresponding parts throughout the several views:

35 Figure 1 is a perspective view of an airplane having its wing structure trussed in accordance with the invention herein disclosed; and

40 Fig. 2 is an end elevation of the wing structure showing the angularity of the combination lift and drift wiring.

The machine illustrated is of the biplane type and includes the usual fuselage 10, landing gear 11, empennage 12, upper sup- 45 porting surface 13 and lower supporting surface 14. The superposed supporting surfaces are interconnected by substantially K-struts 15. These K-struts are best suited to machines of the character disclosed for the 50 reason that they prevent distortion of the wings due to twisting strains. Moreover they offer a minimum of resistance to the air while the machine is in flight and as the

trussing system of this invention is especially adapted to high speed machines such 55 construction is preferred. The invention however may be used in connection with triplanes or multiplanes generally, the illustration of its use in connection with a biplane being only by way of example. 60

Individual lift, drift, stagger and drop wires have been eliminated from the wing structure. The K-struts take the place of the stagger wires usually provided. The spread of the wings being more or less small 65 and the chord proportionately shallow, drop wires need not be used. In lieu of the lift and drift wires, single wire lengths are provided. These wire lengths or wires combinedly function as both lift and drift wires 70 in that they take up a considerable portion of both the lift and drift loads while the machine is in flight. They extend angularly upwardly, outwardly and rearwardly from the front wing beams 16 of the lower wings 75 14 at the inner ends thereof (at the points where the wings are fastened to the fuselage 10) to the outer ends of the rear wing beams 17 of the upper wings 13 (at the points where the K-struts 16 engage). By extending the wires, which are designated as 18, rearwardly they are made to function as drift wires and by extending them upwardly and outwardly they are made to function as lift wires. Thus the single wire lengths at 80 opposite sides of the fuselage serve a two-fold purpose and as a result cut down the resistance of the machine considerably. In fact, they constitute the only wires which are needed in the formation of the wing 85 structure truss and as a number of wires have heretofore been used it is evident that a much improved trussing system has accordingly been evolved. The attachment of the wires 18 at the inner ends forwardly of 90 the point of attachment of the wires at the outer ends is important. It is this arrangement which renders them useful for taking up drift strains on the wings. Especially is the wiring arrangement useful in connection 95 with K or similar struts for the reason that such struts interconnect the superposed wings at their outer ends in a manner conducive to absolute rigidity. Furthermore, struts of the K type equally distribute the 100 105 compression stress upon both wing beams

of the lower wings. In other words, the arrangement disclosed is conducive to maximum strength with a minimum number of wires, *i. e.*, the ideal truss for airplanes of 5 the speed scout type.

While I have described my invention in detail in its present preferred embodiment, it will be obvious to those skilled in the art after understanding my invention, that 10 various changes and modifications may be made therein without departing from the spirit or scope thereof, I aim in the appended claims to cover all such modifications and changes.

15 What is claimed is:

1. A wing structure truss for airplanes having a single exposed wire at each side of the fore and aft axis of the craft to care for both the lift and drift stresses, the wire 20 in each instance being extended rearwardly and outwardly at an angle.

2. A wing structure truss for airplanes having but two exposed wires to care for both the lift and drift stresses, said wires 25 being arranged respectively at opposite sides

of the fore and aft axis of the craft to extend rearwardly and upwardly at an angle.

3. A wing structure truss for airplanes having a single exposed wire at each side of the fore and aft axis of the craft to care for 30 both the lift and drift stresses, the wire in each instance being extended rearwardly and outwardly at an angle and being confined in each instance to the gap between the airplane wings.

4. A wing structure truss for airplanes having but two exposed wires to care for both the lift and drift stresses, said wires being arranged respectively at opposite sides 40 of the fore and aft axis of the craft to extend rearwardly and upwardly at an angle and being in each instance confined to the gap between the airplane wings, the wires at their forward lower ends connecting with the front wing beams of the lower wings 45 and at their upper rearward ends with the rear wing beams of the upper wings.

In testimony whereof I hereunto affix my signature.

GLENN H. CURTISS.
